UNITED STATES PATENT OFFICE.

JACOB B. GABELINE, OF BURLINGTON, IOWA, ASSIGNOR TO STANDARD FOUR TIRE COMPANY, OF KEOKUK, IOWA, A CORPORATION OF IOWA.

DESIGN FOR AN AUTOMOBILE-TIRE.

55,459.

Specification for Design. Patented June 15, 1920.

Application filed March 4, 1920. Serial No. 363,325. Term of patent 7 years.

To all whom it may concern:

Be it known that I, JACOB B. GABELINE, a citizen of the United States of America, residing at the city of Burlington, State of Iowa, have invented a new, original, and ornamental Design for an Automobile-Tire, of which the following is a specification, reference being had to the accompanying drawing, forming a part thereof.

In the drawings, Figure 1 is a plan view of a portion of a tire showing my new design and Fig. 2 is a cross section.

I claim:

The ornamental design for an automobile tire as shown.

JACOB B. GABELINE.
